GRINDING MILL

Harry P. Guillo, New York, N. Y., assignor to
General Printing Ink Corporation, New York,
N. Y., a corporation of Delaware

Application January 20, 1933, Serial No. 652,744

21 Claims. (Cl. 83—12)

This invention is directed to an improvement in grinding mills, and more particularly to a means for attaching the side boards to provide for their adjustment or removal from operative 5 cooperation with the rolls.

Mills of the type with which the invention is more particularly concerned include a pair of revolving drums or rollers, between which the ingredients are repeatedly passed, with subsequent reduction of the space between the rollers until the material is reduced to the requisite fineness. To prevent spreading of the mass in the direction of the axes of the rollers, side boards are used, and these side boards have 15 their lower edges conforming to and closely fitting the periphery of the rollers for an appreciable distance beyond the grinding area of the rollers.

In the use of such a mill it is frequently necessary to reduce the space between the side boards to accommodate different quantities of material, and also necessary to move the side boards away from the rollers for convenient cleaning.

The present invention is directed particularly 25 to the mountings for the side boards, providing a simple, convenient means for relative adjustment of the boards axially of the rollers, and a further means by which the side boards or either of them may be readily and conveniently 30 moved in a direction away from the rollers, as may be necessary from time to time.

The invention in a preferred form and construction is illustrated in the accompanying drawing, wherein:—

35 Figure 1 is a view in side elevation illustrating the side board support according to the invention, a portion of the rollers and the side board in operative relation thereto being shown in full lines and the movement of the side boards to 40 an inoperative position relative to the rollers being shown in dotted lines.

Figure 2 is a side elevation of the construction shown in Figure 1.

45 Figure 3 is a broken vertical section on the line 3—3 of Figure 1.

The conventional parts of a grinding mill necessary to an understanding of the present invention are illustrated as including cooperating rolls 1 and 2 and an end board 3, it being 50 understood that the end board and the details of support and connection of said board are duplicated for the opposite end of the rolls. The board 3 at each end is formed at its lower portions with arcuate edges 4 which are coincident 55 with the peripheral surfaces of the rolls, the

apex or meeting point 5 of these arcuate edges fitting down close to the grinding area of the rolls when the board is in operative position.

A bracket arm 6 is secured in the vertical median line of the board 3, the lower end of the bracket arm being laterally enlarged at 7 and formed centrally with a longitudinally ranging slot 8 to slidably fit over a bolt 9 secured in the end board 3 and projecting outwardly therefrom. The bolt 9 may be provided with a securing nut 10 to overlie the walls of the slot, and the lower end of the bracket is provided with an adjusting screw 11 which may be set to engage with the bolt 9 to properly position relatively the board and bracket. The lateral enlargement 7 of the lower end of the bracket is held against play relative to the board by set screws 12 which bear against the board as shown.

The upper end of the bracket arm 6 above the board is provided with a block 13 projected at right angles to the arm with its length parallel to the similar dimension of the board. The upper end of the block 13 has an undercut guiding projection 14 on its upper edge adapted to 75 slidably cooperate with a complementarily formed guideway 15 in an upper block section 16, the top wall of which latter block section is formed with an opening 17 to receive a bolt 18 headed below the opening to prevent independent 80 upward movement. The bolt 18 slides between frame bars 19 which are arranged above and parallel to the axes of the rolls 1 and 2 and in line with the grinding point of the rolls. The threaded upper end of the bolt 18 is provided 85 with a securing member, preferably in the form of a hand wheel 20, overlying the upper surface of the bars 19.

The guideway 15 and cooperating guide projection 14 on the block 13 are formed on an 90 arcuate plane from a center coincident with the center of one of the rolls 1 and 2, and the upper block section 16 is provided with a removable end stop 21 removably secured by a bolt 22 to prevent relative movement of the block sections 13 and 16 in one direction, such movement 95 in the opposite direction, however, being free when desired to remove the end board.

The block section 13 is provided with a transverse shaft 23, on one end of which is secured 100 a hand lever 24 and on the opposite end of which is secured a disk 25 having a lateral pin 26 to provide with the disk an operating crank. Carried by and loosely depending from the crank pin 26 is a rod 27 on which is threaded an ad- 105

justing nut 28. Normally the rod 27 aligns with a similar rod-like projection 29 from the upper edge of the board 3 and between the board and the adjusting nut 28 and encircling 5 the rod sections 27 and 29 is a coiled spring 30, the tension of which may be obviously adjusted by the nut 28.

By reason of the crank structure described, it is apparent that through operation of the 10 hand lever 24, the crank pin 26 may be arranged at its lowest point of throw or at any point above such lowest point by movement of the lever. When the crank pin is in its lowest point of throw, the spring is naturally compressed and pressure is applied on the upper 15 edge of the board to thereby substantially lock the block sections 13 and 16 in operative relation, as shown in full lines in Figure 1. The arrangement is such that when the crank pin 20 is in the position of maximum holding effect, the lever is vertical, aligned with the bracket 6, and limited in further movement in one direction by a stop 31 carried by the block section 16 and cooperating with the projecting portion 25 of the lever.

In this locking position of the parts, it will be apparent from the drawing that the spring rod including the section 29 is permitted to move slightly past the center position, thus serving as 30 a lock for the whole device when the upper end of the lever 24 is against the stop 31. By reason of this stop 31, the lever 24 is movable in but one direction, i. e. toward the left in Figure 1, and may be moved in this direction to the limit 35 permitted by a stop 33 carried by the block section 13. When the lever is in this latter or inoperative position, the crank pin 26 is raised from its lowermost position, the tension of the spring relieved, and the block section 13 40 may then be moved laterally or toward the left as controlled by the track 15 of the block section 16, and as the plane of this movement is exactly coincident with the periphery of the grinding roll, it is apparent that the board as a whole 45 following this movement will follow the periphery of one roll and be moved wholly from cooperation with the other roll. This position is indicated in dotted lines in Figure 1. As previously stated, the opposite end board is supported in an exactly identical manner and, of course, may be operated and controlled in the same way.

The board 3 is permitted a limited vertical movement by the construction described being 55 guided by the lower connection of the bracket arm 6 and further by a pin 34 carried by the board and engaging in a slot 35 in a portion 36 of the bracket arm 6 which directly overlies and bears against the board 3. The relative limited 60 movement of the side board is controlled by the bolt 9 moving in the slot 8. The adjusting screw 11 serves to limit the travel of the board toward the roll and thus definitely determines the space between the edges of the board and the 65 periphery of the rolls. The set screws 12 bear against the surface of the board with sufficient tension to hold the board firmly to the bracket arm 6 to prevent any possibility of wobbling of the side board without, however, interfering with the limited vertical play of the board just described. As a result of the construction, the respective boards may be adjusted toward and from each other axially of the rolls by loosening the locking means 20 and thus freeing the blocks, bracket arm and boards for longitudinal move- 70 75

ment between the bars 19. Either board at will, when in operative position, may be readily removed therefrom to permit necessary cleaning or for any other purpose by shifting the lever 24 in the direction indicated in dotted lines in Figure 1 to materially reduce the tension of the spring 30 and thus permit the bracket 6, block section 13 carried thereby, and board 3 secured thereto to be swung in a path coincident with the periphery of one of the rolls so that the board will move around one of the rolls, away from the other, and away from the grinding line of the rolls, all as clearly indicated in dotted lines in Figure 1 of the drawing. 80 85

Obviously, complete removal of the board is 90 facilitated by swinging the block section 13 wholly free of the guideway 15, whereupon all connections of the board proper with the upper block section 16 are removed and the board as a whole may be lifted entirely free from the rolls. 95

I claim:—

1. A mill including grinding rolls, a side board at each end of the roll, the side boards having roll-cooperating edges corresponding in contour with that of the rolls, means for adjusting the side boards toward and from each other, a standard connected to each side board, a block 100 guidingly receiving the upper end of the standard, the guiding means of the block forming a guiding path for standard movement concentric with the surface of one of the rolls. 105

2. A mill including grinding rolls, a side board at each end of the rolls, the roll-cooperating edges of the side boards corresponding in contour with the peripheries of the rolls, a 110 standard connected to each side board, a block carried by the upper end of the standard, a second block supported above the standard, the meeting faces of the blocks being formed for 115 sliding engagement on a path concentric with the surface of one of the rolls.

3. A mill including grinding rolls, a side board at each end of the rolls, the roll-cooperating edges of the side boards corresponding in contour with the peripheries of the rolls, a 120 standard connected to each side board, a block carried by the upper end of the standard, a second block supported above the standard, the meeting faces of the blocks being formed for 125 sliding engagement on a path concentric with the surface of one of the rolls, and spring means between the side board and the standard-carried block for clamping the blocks against movement. 130

4. A mill including grinding rolls, a side board at each end of the rolls, a standard connected to each side board, a block carried by the upper end of the standard, a second block supported above the standard, the meeting faces of the blocks being formed for 135 sliding cooperation on a path concentric with the surface of one of the rolls, spring means for clamping the blocks against movement, and a lever for operating the spring means. 140

5. A mill including grinding rolls, a side board having an edge for cooperating with the rolls and of a contour corresponding to that of the roll periphery, a standard connected to the side board, a block secured to the upper end of the standard, a second block mounted for adjustment longitudinally of the rolls, said blocks being designed for sliding engagement on a path concentric to the surface of one of the rolls, a crank carried by the block secured to the standard, a spring interposed between said crank and the adjacent side board, and a lever for operat- 145 150

ing the crank to tension or release the spring for holding the blocks against or permitting their relative movement.

6. In a mill, grinding rolls, a side board at each end of the rolls, a standard connected to the side board, a block secured to the upper end of the standard, a second block mounted for adjustment longitudinally of the rolls, said blocks being designed for sliding cooperation on a path concentric to the surface of one of the rolls, a crank carried by the block secured to the standard, a spring interposed between said crank and the adjacent side board, a lever for operating the crank to tension or release the spring for holding the blocks against or permitting their relative movement, and means carried by the respective blocks for limiting relative movement of the lever.

7. A mill including grinding rolls, side boards having roll-cooperating edges corresponding in contour to the peripheries of the rolls, a standard adjustably connected to each side board, a block carried by the upper end of the standard, a second block supported above the standard, the leading faces of the blocks being in engagement and formed for sliding cooperation on a path concentric with the surface of one of the rolls, a spring rod between one of said blocks and the side board for clamping the blocks against movement, and a lever for operating the rod.

8. A mill including grinding rolls, side boards having roll-cooperating edges corresponding in contour to the peripheries of the rolls, a standard adjustably connected to each side board, a block carried by the upper end of the standard, a second block supported above the standard, the leading faces of the blocks being in engagement and formed for sliding cooperation on a path concentric with the surface of one of the rolls, a spring rod between one of said blocks and the side board for clamping the blocks against movement, a lever for operating the rod, and means for limiting the movement of the lever in locking position, the spring rod when the lever is in locking position being carried beyond center to utilize the spring as an additional locking means.

9. A mill including grinding rolls, a side board at each end of the rolls, standards, a set screw connecting each standard to one of the side boards, cooperating bearing blocks for the upper end of the standard having their meeting faces on a path concentric with the surface of one of the rolls, and manually controlled means for locking the blocks against movement and for releasing the blocks for sliding cooperation.

10. A mill including grinding rolls, a side board having roll-cooperating edges of a contour corresponding to that of the periphery of the rolls, standards connected to the side board, the connection providing for adjustable limited movement between the standard and side board, and means for supporting the standard for bodily movement in an arcuate path.

11. A mill including grinding rolls, a side board having roll-cooperating edges of a contour corresponding to that of the periphery of the rolls, a standard, a bolt engaging the board and movable in a slot in the standard, a set screw for limiting the relative movement of the bolt and standard in one direction, and manually operable means for fixing the side board and standard at the limit of play permitted by the set screw.

12. A mill including grinding rolls, a side board having roll-cooperating edges of a contour corresponding to that of the periphery of the rolls, a standard, a bolt secured to the board and movable in a slot in the standard, a set screw to adjustably limit movement of the bolt in one direction in the standard, and means carried by the standard and cooperating with the board to prevent relative movement of the board and standard other than that permitted by the bolt.

13. A mill including grinding rolls, a side board having roll-cooperating edges of a contour corresponding to that of the periphery of the rolls, a standard for supporting the side board, said standard being formed with a longitudinal slot, a bolt passing through said slot and fixed to the side board, a set screw adjustably mounted in one end of the slot to limit movement of the bolt relative to the slot in one direction, a pin carried by the standard remote from the slot, said board being formed with a recess to receive the pin to guide the board in movement relative to the standard.

14. A mill including grinding rolls, a side board having roll-cooperating edges of a contour corresponding to that of the periphery of the rolls, a standard for supporting the side board, said standard being formed with a longitudinal slot, a bolt passing through said slot and fixed to the side board, a set screw adjustably mounted in one end of the slot to limit movement of the bolt relative to the slot in one direction, a pin carried by the standard remote from the slot, said board being formed with a recess to receive the pin to guide the board in movement relative to the standard, and means carried by the standard and bearing upon the board in both directions beyond the bolt.

15. A mill including grinding rolls, a side board having roll-cooperating edges of a contour similar to that of the periphery of the rolls, an element carried by and movable with the side board, and a member having sliding engagement with the element, the relatively slidable engaging parts of the element and member defining an arcuate path having a center substantially coincident with the center of the roll through which the element and thereby the side board is moved in operation.

16. A mill including grinding rolls, a side board having roll-cooperating edges of a contour similar to that of the periphery of the rolls, an element carried by and movable with the side board, and a member having sliding engagement with the element, the relatively slidable engaging parts of the element and member defining an arcuate path through which the element and thereby the side board is moved in operation, said arcuate path substantially corresponding in curvature to that of the periphery of the rolls.

17. A mill including a grinding roll, side boards having roll-cooperating edges of a contour corresponding to that of the periphery of the rolls, a standard carried by each side board, an element carried by the standard, a member engaged by the element, the engagement of the member and element permitting sliding movement of the element with respect to the member in an arcuate path corresponding substantially to the periphery of the rolls, whereby movement of the element along such arcuate path compels similar movement of the standard and side board.

18. A mill including grinding rolls, side boards having edges cooperating with the rolls and of a contour corresponding to the periphery of the rolls, a standard connected to the side board for limited free movement with respect thereto, a block carried by the upper end of the standard, a second block with which the standard-carried block engages for sliding cooperation, the engaging faces of the blocks presenting an arcuate path corresponding substantially to the periphery of a roll, and manually operable means whereby the blocks may be held against free sliding cooperation. 80
19. A mill including grinding rolls, side boards having edges cooperating with the rolls and of a contour corresponding to the periphery of the rolls, a standard connected to the side board for limited free movement with respect thereto, a block carried by the upper end of the standard, a second block with which the standard-carried block engages for sliding cooperation, the engaging faces of the blocks presenting an arcuate path corresponding substantially to the periphery of a roll, manually operable means whereby the blocks may be held against free sliding cooperation. 85
20. In a mill, grinding rolls, side boards having roll-cooperating edges corresponding in contour to the periphery of the rolls, and a support for the side boards, said support comprising cooperatively engaged relatively sliding parts formed to compel such relative sliding movement to follow an arcuate path having a center substantially coincident with the center of one of the roll cooperating edges of the side boards. 90
21. In a mill, grinding rolls, side boards having roll-cooperating edges corresponding in contour to the periphery of the rolls, and a support for the side boards, said support comprising cooperatively engaged relatively sliding parts formed to compel such relative sliding movement to follow an arcuate path, said arcuate path being concentric with the curvature of the periphery of the rolls. 95
